UNITED STATES PATENT OFFICE.

EDWARD I. HORSMAN, JR., OF NEW YORK, N. Y., ASSIGNOR TO E. I. HORSMAN CO., OF NEW YORK, N. Y., A CORPORATION OF NEW YORK.

DESIGN FOR A TOY CAT.

42,755.

Specification for Design.

Patented July 9, 1912.

Application filed April 27, 1912. Serial No. 693,741. Term of patent 3½ years.

To all whom it may concern:

Be it known that I, EDWARD I. HORSMAN, Jr., a citizen of the United States, and resident of the borough of Manhattan, city, county, and State of New York, have invented a new, original, and ornamental Design for a Toy Cat, of which the following is a specification.

Reference is to be had to the accompanying drawing which shows a perspective view of a toy cat embodying my new design.

The design comprises a body of furry material and grotesque legs of similar mate-

rial. The body is provided with a furry upstanding tail and a cat's head of substantially smooth material. A ribbon surrounds the neck of the toy and has its ends tied in a bow.

I claim:

The ornamental design for a cat as shown and described.

EDWARD I. HORSMAN, JR.
